LOCK

Carroll Woodruff, Joliet, Ill., assignor of one-tenth to Ernest Radtke and Adele Radtke, five per cent to Frank Kraemer, five per cent to R. E. Waugh, five per cent to Dwight Gordon, and thirty-three and one-third per cent to Dring Harper, Chicago, Ill.

Application August 28, 1940, Serial No. 354,607

4 Claims. (Cl. 70—364)

This invention pertains to locks, and more particularly to those utilizing a cylinder and a plurality of tumblers or pins.

In the present forms of cylinder and pin locks, there are usually two cylinders and a plurality of pins which are normally spring-pressed into bores which extend through into the keyway. The pins are made each in two sections, so when the proper key is inserted the breaks between the upper and lower sections coincide with the line between the stationary and revolving cylinder permitting the latter to revolve and the lock to open. This construction creates the disadvantage that, when a pry is used, the pins will bind between the stationary and revolving cylinder and, by utilizing a pick, the breaks can be gotten into position so the lock will open. I realize that the lock art has long engaged the attention of experts but, so far as I am aware, no one has obviated the above mentioned disadvantage by the specific advantageous structure embodied in my invention.

The object of my invention is safety in locks.

Another object is to produce a substantially unpickable lock.

A further object is to produce an easily manufactured and readily operated lock for accomplishing the above results.

These and other objects may be accomplished by my invention which embodies among its features a lock having a stationary cylinder, a rotatable or locking cylinder therein, a second or key cylinder concentric thereto, a plurality of bores and pins extending through from the stationary cylinder to the keyway, said pins each having a break near the line between the stationary cylinder and the locking cylinder, an additional break near the line between the locking cylinder and the key cylinder and bores extending between the locking cylinder and the key cylinder containing loose pins to provide play therebetween so the key cylinder will turn sufficiently to prevent the remainder of the first mentioned pins from being displaced by the lower portions of these pins when it is so turned. Thus, no binding can be accomplished by turning the key cylinder. It is to be understood that this cylinder may be formed of a plurality of identical discs carrying the pins and bores.

These and other objects and features will become evident from the following disclosure when taken in connection with the accompanying drawing in which:

Figure 1 is a cross-section of a lock embodying my invention,

Figure 2 is a cross-section taken on line 2—2 of Figure 1.

Figure 3 is the device shown in Figure 2 but with the key cylinder turned,

Figure 4 is an exploded view, in perspective, of the discs forming the key cylinder, and,

Figure 5 is a perspective view of the discs shown in Figure 4 assembled into the locking cylinder.

Referring to the drawing in detail, my improved lock consists of a casing 10 which holds stationary a cylinder 11 having bores 12 therethrough. Revolvably positioned in the cylinder 11 is a locking cylinder 11a having bores 13, coinciding with bores 12 and also a corresponding number of holes 14 at right angles to bores 12 and threaded to receive plugs for a purpose to be hereinafter described. Revolvably held in this locking cylinder is a key cylinder consisting of a number of discs 15. These discs have a keyway 16 and also have bores 17 coinciding with bores 13 and leading into keyway 16. There are also sockets 18 coinciding with bores 14.

When the lock is assembled the key cylinder 25 consisting of the disks 15 is inserted in the locking cylinder 11a, and play pins 19 are inserted in the side bores 14, being held therein by plugs 20. The play pins 19 do not snugly fit the bores 14 and sockets 18, so as to leave a certain amount 30 of play between the disks 15 and locking cylinder 11a. The locking cylinder is inserted into the stationary cylinder, and pins, made up of three sections 21, 22 and 23, are inserted into bores 12, 13 and 17 and held therein by springs 35 24. It will be noted that these pins provide a break between the locking cylinder 11a and the stationary cylinder 11, and also between the disks 15 and locking cylinder 11a. At the latter break, pins 22 are made with rounded bottom ends and 40 pins 23 are made with flat top ends in order to effectively abut the locking cylinder upon insertion of a pick, with the key cylinder sections angularly arranged so that the inner pin sections are out of alignment with the outer sections. 45 When the locking mechanism is assembled as explained above, stationary cylinder 11 is inserted into casing 10 and held therein by set screw 25.

When the lock is in use, if an attempt is made to pick the lock by exerting torsional stress by 50 rotation of the disks 15 in an attempt to bind the pin tumblers, play pin 19 will allow the disks 15 to assume the position shown in Figure 3. Then lower pin section 23 abuts cylinder 11a and will prevent all manipulation of the upper pin sections 21 and 22. Since cylinder 11a is inac-

cessible by reason of the front of casing 10, the exertion of a lifting force on the tumbler pins by the "letting up" method of picking is prevented and the lock is, to all intents substantially unpickable by any method which is generally known to malefactors.

When a key is inserted in keyway 16 it contacts the bottom pins 23 and causes the break between pins 21 and 22 to fall between locking cylinder 11a and stationary cylinder 11, and the lock can be opened similarly to the conventional lock. Accordingly, it will be seen that I have produced an easily operated and assembled lock which is substantially unpickable. Although a preferred embodiment is disclosed herein, I do not wish to be limited thereto but only by the scope of the appended claims.

What is claimed is:

1. In a lock, a stationary cylinder, a locking cylinder rotatably held therein, a keyway cylinder formed of discs rotatably held in the locking cylinder, three sectioned pins extending from the stationary cylinder into the keyway and of such a length that, when a key is inserted, they will break between their upper and middle sections and permit rotation of the locking cylinder, the lower ends of the middle sections of the pins being rounded and the upper ends of the lower sections flat so that, when the discs are turned slightly with respect to the locking cylinder the flat ends abut the cylinder and prevent manipulation of the other pin sections, and a play pin between each disc and the locking cylinder to permit limited movement within the locking cylinder.

2. In a lock of the character described, a body having a cylindrical bore, a tubular locking cylinder rotatably mounted in the said bore, a keyway cylinder rotatably fitted within the said locking cylinder, a plurality of tumbler pins slidably fitted in radial bores in the cylinders and body, each of the said pins having a plurality of aligned sections spring pressed to normally lock the cylinders and operative to release the same

upon insertion of a key, and means connecting the keyway cylinder with the locking cylinder in such manner as to allow limited angular movement of the keyway cylinder.

3. In a lock of the character described, a body having a cylindrical bore, a tubular cylinder rotatably mounted in the said bore, a keyway cylinder rotatably fitted within the tubular cylinder, the said keyway cylinder being composed of a plurality of transversely divided sections, each of the said sections having a radial bore adapted for alignment with corresponding bores in the tubular cylinder and the body, a tumbler pin slidably fitted in each set of aligned bores, each of the said tumbler pins being composed of three transversely divided sections, a spring mounted in each bore in the body yieldingly forcing the tumbler pin therein to retracted position for locking the tubular cylinder against rotation in the body, the said pin being retractable upon the insertion of a key in the keyway cylinder to align breaks between the pin section for rotation of the tubular cylinder, and pins mounted in and projecting radially inward of the tubular cylinder and engaging sockets in the key cylinder sections to allow limited angular movement of the sections within the tubular cylinder.

4. In a lock of the character described, a body having a bore therein, a locking cylinder rotatably mounted in the said bore, a plurality of keyway cylinder forming sections rotatably fitted within the said locking cylinder, a plurality of tumbler pins slidably fitted in radial bores in the said cylinders and in the body, each of the said pins having a plurality of aligned sections spring pressed to normally lock the cylinders and operative to release the same upon insertion of a key, and pins mounted in and projecting radially inward of the locking cylinder and engaging sockets in the keyway cylinder sections so as to allow limited angular movement of the said sections within the locking cylinder.

CARROLL WOODRUFF.
